UNITED STATES PATENT OFFICE

OSCAR L. LAWSON, OF LYNN, MASSACHUSETTS, ASSIGNOR TO UNITED SHOE MACHINERY CORPORATION, OF PATERSON, NEW JERSEY, A CORPORATION OF NEW JERSEY

SHOE SEWING MACHINE

Original application filed June 12, 1929, Serial No. 370,343. Divided and this application filed November 5, 1931. Serial No. 573,041.

The invention relates to shoe sewing machines and is herein disclosed as embodied in a lockstitch horn shoe sewing machine of the McKay type for sewing together the 5 insole, upper, and outsole of a shoe.

The object of the invention is to provide certain mechanisms of modified and improved construction and operation which are particularly adapted for use in a machine 10 of this description and contribute in producing a more efficient and economical machine which will operate smoothly and accurately at higher speeds than previously attained without excessive wear and tear 15 on the parts.

The lockstitch shoe sewing machine herein described and illustrated, is of the general type shown and described in the patent to James H. Reed, No. 1,688,056, dated 20 October 16, 1928, for sewing the outsole to the insole and associated upper of a shoe. The machine herein disclosed includes a straight hooked needle and a shuttle, as in the machine of the above-mentioned patent, 25 at the upper side of the work, a whirl containing horn on which the work is supported, a presser foot, and an awl which acts to feed the work, together with take-up and stitch setting mechanism to draw the needle 30 loop over the shuttle and set the stitch.

In order to permit the work to be fed quickly and accurately into position for each successive stitch, the present invention contemplates the provision of a novel and improved mechanism for imparting to a feeding element adapted to engage with the work a positive four-motion feeding movement.

The several features of the invention consist also in the devices, combinations, and arrangement of parts hereinafter described and claimed which, together with the advantages to be obtained thereby, will be readily understood by one skilled in the art from 40 the following description taken in connection with the accompanying drawings in which Fig. 1 is a view in left side elevation of the head of a lockstitch shoe sewing machine embodying the several features of the 45 invention; Fig. 2 is a view in front eleva-

tion of the head of the machine shown in Fig. 1; Fig. 3 is an enlarged view in right side elevation of a portion of the head of the machine; Fig. 4 is a sectional plan view taken on the line 4-4 of Fig. 2; and Fig. 5 is a view in front elevation of the parts shown in Fig. 4 viewed from the plane indicated by the line 5-5 on Fig. 4.

Referring to the drawings, the straight hooked needle of the machine is indicated 55 at 8 secured to the lower end of a needle bar 10, the shuttle at 12 provided with a shuttle hook 14 for passing the needle loop around the shuttle, the presser foot at 16, the awl at 18, and the work supporting horn at 20.

In order to permit the work to be fed accurately and certainly past the stitch forming devices, a positive four-motion feeding movement is imparted to the awl 60 through mechanism which embodies certain 65 features of the present invention. The awl is secured to the lower end of an awl carrier 76 which is mounted to slide vertically in a slot formed in an awl carriage 78. Two parallel links 80 pivoted at points 82 on the 70 machine frame are provided to support the carriage for movement substantially in the line of feed. With this construction, a high 75 speed of operation may be readily attained without undue vibration or inaccuracy in 80 the operation of the parts. The operating connections from the cam shaft 48 for moving the awl vertically to and from the work and horizontally in the line of feed comprise a rock shaft 86 which is journaled in 85 bearings 88 and 90 in the machine frame and carries at its forward end a lever arm 92. Movement is transmitted from the lever 92 to move the awl vertically towards and 90 away from the work by means of a sliding connection with the upper end of the awl carrier 76 which comprises a cam block 94 pivotally secured to the end of the lever arm 92 and adapted to slide in a horizontal slot 96 formed in the upper end of 95 the awl carrier 76. The rock shaft 86 is given an oscillatory movement for each rotation of the cam shaft 48 through connections including a cam lever 98 which is 100 loosely sleeved to the rock shaft 86 and is

provided with a cam roll 100 to engage in a cam path in the cam disk 102 on the cam shaft 48.

In order to permit an adjustment of the vertical limits of movement of the awl with relation to the work, means are provided for adjusting the initial position of the rock shaft 86 and lever 92 with relation to the positively actuated cam lever 98 comprising a flange 104 formed on the hub of the lever 98 which is engaged on either side by two set screws 106 in a sleeve 108 fixed on the rock shaft 86 by means of a set screw 110.

15 A reciprocatory movement is imparted to the carriage 78 in the line of feed from the cam shaft 48 through connections which include a sleeve 112 which surrounds the rock shaft 86 and is provided at its forward end 20 with a lever arm 114 off-set from the sleeve. The lever arm 114 and the sleeve 112 are oscillated through a definite arc for each cycle of operations of the machine by means of a cam lever 116 which is loosely sleeved 25 on the rock shaft 86 and is positively operated by the engagement of a cam roll 118 in a corresponding groove in the face of the cam disk 120. An adjustable connection is provided between the cam lever 116 and the 30 sleeve 112 which comprises a flange 122 formed on the hub of the cam lever 116 and two set screws 124 mounted on the sleeve 112 to engage the flange between them. The carriage 78 is actuated from the lever arm 35 114 through connections which are adjustable to vary the length of the feeding stroke imparted to the awl without varying the forward limit of the awl stroke which must remain constant to cooperate properly with 40 the other sewing elements of the machine. These connections comprise a bracket 126 which is mounted for adjustment on ways 128 on the lever arm 114 and is held in adjusted position on the arm 114 by means of 45 two small set screws 130. The bracket 126 is also provided with a pin or roll 132 which is adapted to ride in a vertical slot 134 formed in the rear end of the carriage 78. With this arrangement and construction 50 of the parts, it will be seen that the length of the feeding stroke will be varied in proportion as the bracket 126 is moved in or out along the ways 128 on the lever 114. In order to maintain the forward limit 55 of movement of the awl constant for any adjustment of the bracket 126, the downward or feeding stroke of the lever 114 is limited to bring the ways 128 to a vertical position.

60 This application is a division of applicant's pending application for shoe sewing machines, filed June 12, 1929, Serial No. 370,343.

65 The nature and object of the invention having been indicated, and a machine em-

bodying the several features of the invention having been described, what is claimed is:

1. A shoe sewing machine having, in combination, sewing devices including a hook 70 needle, a presser foot, a work support, a carriage, parallel links on which the carriage is supported to permit reciprocation thereof in the line of feed, an awl carrier mounted in the carriage for vertical movement, a rock 75 shaft, connections therefrom for moving the awl carrier vertically, a sleeve on the rock shaft, and connections therefrom for imparting a reciprocating movement to the carriage.

15 2. A shoe sewing machine having, in combination, sewing devices including a hooked 80 needle, a presser foot, a work support, a carriage mounted to reciprocate in the line of feed, an awl carrier mounted in the carriage for vertical movement, means for actuating the awl carrier comprising a rock shaft and an arm on the rock shaft engaging the awl carrier, a sleeve on the rock shaft, and connections from the sleeve for imparting 85 a reciprocating movement to the carriage.

3. A shoe sewing machine having, in combination, devices including a hooked needle, a presser foot, a work support, a carriage, parallel links on which the carriage is supported to permit reciprocation thereof in the line of feed, an awl carrier mounted in the carriage for vertical movement, means for actuating the awl carrier, a lever for actuating the carriage, and a pin and slot connection 90 between the lever and carriage.

In testimony whereof I have signed my name to this specification.

OSCAR L. LAWSON.
